UNITED STATES PATENT OFFICE.

SAMUEL P. SMURR, OF CHICAGO, ILLINOIS, ASSIGNOR TO VARIETY MANUFACTURING COMPANY, OF CHICAGO, ILLINOIS, A CORPORATION OF ILLINOIS.

CLOSURE OPERATOR.

1,416,071.

Specification of Letters Patent. Patented May 16, 1922.

Application filed February 3, 1919. Serial No. 274,654.

To all whom it may concern:

Be it known that I, SAMUEL P. SMURR, a citizen of the United States, residing at Chicago, in the county of Cook and State of

5 Illinois, have invented a certain new and useful Improvement in Closure Operators, of which the following is a full, clear, concise, and exact description, reference being had to the accompanying drawings, forming 10 a part of this specification.

My invention relates to improvements in vertically movable closures for door and window openings and has special reference to improved means for counterbalancing 15 such closures.

In rolling fire shutters, lifting doors, etc., it is necessary to provide means which shall substantially counterbalance the weight of such closures to the end that they can be 20 opened and closed easily. In some closures, for instance rolling fire shutters, it is necessary that the counterbalancing effect be automatically variable to correspond with the variable weight of the depending part

25 of the shutter, viz: smaller when the shutter is wound up and larger when the shutter is unwound. To accomplish this purpose many devices have been developed in which a coiled tension spring is wound up as the

30 shutter descends, thus increasing the counterbalancing force. There are certain inherent defects in this form of counterbalance, the chief of which are the cost of such springs, as they have to be made of large, heavy steel wire or rods, and the unreliability of such springs, due particularly to the necessity for attaching the ends of the springs to operating parts in a manner to resist the tension to which the springs are 35 subjected.

This connection is frequently accomplished by bending the ends of the springs at an angle and clamping or hooking them to an operative part, but such bending and clamping produces possibilities 40 of weakness which frequently develop into broken springs with all their attendant and following expense of repairs and possibility of break down at a critical time.

By means of my invention I am enabled 45 to retain the advantages of the coiled spring and to eliminate the detrimental features

above spoken of and to provide a counterbalance which is not only reliable but is also capable of being manufactured at relatively low cost.

These advantages are based on the fact that I provide means for making the expansive force of a coiled compression spring effective as a counterbalancing force, and in doing this it is not necessary to distort or attach the ends of the spring. So far as I am informed, I am the first to so employ or apply a coiled compression spring and in doing so I provide mechanism to convert the rectilinear expansion of a coiled compression spring to produce relative rotation between two members for rolling and unrolling fire shutters, or for winding up or unwinding cables for operating lift doors, etc. Upon a full understanding of my invention it will be seen that my invention is not limited in its application to closures but that it can readily be made use of in other mechanisms wherein it is desirable to produce a limited relative rotation of two members.

The essence of my invention resides in the association of two rotatable members, a coiled compression spring arranged between them, the expansive power of the spring made available to relatively rotate said members by a quick thread screw and nut thereon, the nut caused to travel on the screw by the pressure of the spring.

It will be understood, of course, that various details of construction are required to operatively relate these elements and it should be understood that they may be related in many ways to produce desired results, that instead of the elements both rotating, either one may be held stationary and the other rotate, that the elements may be arranged as a shaft within a tube or drum, or in other relations, the essential feature being that a coiled compression spring is used with means for converting the rectilinear movement of the spring as it expands into a rotary movement of one element or of the relative rotative movement of two elements.

My invention will be more readily understood by reference to said drawings, in which I have illustrated the application of my in-

vention to a rolling fire shutter and to a horizontal folding door; and

Figure 1 is a fragmentary elevational view, partly in section, of a rolling fire shutter made in accordance with my invention;

Figures 2 and 3 are detail vertical sections on the lines 2-2 and 3-3 respectively of Figure 1;

Figure 4 is an elevational view of a horizontal folding door in combination with a counterbalancing device made in accordance with my invention;

Figure 5 is a vertical section on the line 5-5 of Figure 4;

Figure 6 is a central longitudinal section of the counterbalance device shown in Figure 4;

Figure 7 is a vertical sectional view on the line 7-7 of Figure 6;

Figure 8 is a detail vertical section on the line 8-8 of Figure 6;

Figures 9 and 10 are detail vertical sectional views similar to Figures 2 and 3 illustrating various forms of construction embodying the principles of my invention;

Figure 11 is a fragmentary isometric view of the shaft employed in connection with the forms shown in Figures 9 and 10; and Figure 12 is a front elevational view of the drum of a rolling shutter showing the features of construction disclosed in Figure 9 in connection therewith.

In said drawings, 10 is one of the rotatable elements and in Figures 1 to 3 inclusive the other rotatable element 11 is a drum upon which a flexible metal window shutter 12 is adapted to be wound. One end of the curtain is secured to the periphery of the drum by screws 13 and as the drum revolves in one direction or the other the curtain or shutter 12 is raised or lowered as may be, the edges of the curtain being guided in suitable channel guides 14.

The drum 11 is mounted at its ends on heads 15 and 16 and the shaft 10 is centrally mounted and rotatable in the heads. The head 15 is provided with a central projection 17 which is rotatably mounted in a bracket 18 which is secured to and projects from the wall of the building and the outer end of the projection 17 carries a gear 19 by means of which the drum 11 may be rotated to wind and unwind the curtain. I provide a pinion 20 meshing with the gear 19 and a chain wheel 21 rigid with the pinion and a hand chain 22 for rotating the gear 19.

At the opposite end of the drum the head 16 is rotatably mounted on the shaft 10 and the shaft in turn is mounted in a bearing provided in a bracket 23 which is secured to the wall of the building and by which the end of the device is supported. The brackets 18 and 23 form end walls for a curtain casing 13' and the casing is com-

pleted by a sheet metal canopy or cover secured at its ends upon said brackets and at its upper edge to the wall and enclosing the drum and curtain. The drum 11 is secured to the heads by the screws 24 and the heads 70 close the ends of the drum and the drum thus serves as a closed chamber in which to hold lubricant.

My novel form of counterbalance comprises a relatively long pitch screw thread 75 which I provide on the shaft, a nut which is adapted to be moved along the shaft by the rotation of the drum and a compression spring which is adapted to be controlled by the nut. The screw thread is preferably of a long pitch so that the expansive force of the spring will force the nut longitudinally of the shaft and cause the relative rotation of the shaft and drum. In the form shown in Figure 1 the shaft 10 is square 85 within the drum and I heat the shaft and twist it to form the screw threads 25 thereon. I make the threads of substantially 45 degree pitch and being formed by the twisting of the square shaft, the screw is a 90 quadruple screw or thread. I twist enough of the length of the shaft to provide a long enough screw thread to wind up the curtain, in the instance shown substantially three turns of the drum being necessary.

For engaging the threads I provide a large square nut 26 having a smooth hole 27 large enough to allow the twisted shaft to slide through same and I provide thread engaging plugs 28, one for each thread, secured in radial holes 29 provided in the nut 26. I preferably make the holes 29 on the diagonal diameters of the nut, as this provides longer holes than if they were made in the flat sides of the nut. The inner end 30 of each plug is rounded to fit in the screw thread groove in the shaft. The plugs are held tightly in the holes 29 as by being driven into same.

To engage the nut 26 with the drum 11 I provide a tube 31 of square section and of a size to fit loosely on the nut 26 and within which the nut can freely slide, and I secure one end of the tube 31 to a central square projection 32 on the inner end of the head 16 by the screws 33 so that the tube 31 and the drum rotate together. I hold the opposite end 34 of the tube 31 centrally in relation to the shaft 10 by a head or collar 35 which I secure to the shaft 10. The head 35 is circular and while it can form a bearing for the square tube I prefer to form the corners of the tube inwardly at said end 34 so as to assist in holding lubricant within the square tube for lubricating the screw 125 end nut. The head 35 is secured rigidly upon the shaft 10 as by the set screw 36 to rotate therewith. Between the head 35 which is a relatively fixed abutment and the nut 26, which is a relatively movable abut- 130

ment, I interpose a simple coiled compression spring 37. The spring surrounds the shaft 10 within the square tube 31 and is adapted to be compressed when the drum is turned in a direction to unwind the curtain and to be permitted to expand when the drum is turned to wind up the curtain, consequently the force of the spring increases as the curtain descends and thus requires more force to counterbalance it and vice versa. The square tube 31 provides a plurality of longitudinal grooves on the drum in which the nut is engaged and the twisting of the shaft forms spiral grooves on the shaft with which the nut engages, so that longitudinal movement of the nut between these two members causes a relative rotation thereof. It is conceivable that I might effect the relative rotation of these two elements by a single groove in each, that the spiral groove might be in the drum and the straight groove on the shaft and that the essential features might be arranged in any other relation without departing from the spirit of my invention. While, as explained hereinbefore, my balancing device can be arranged to permit either element to rotate, in the form shown in Figure 1 the drum rotates and I hold the shaft 10 against rotation. For this purpose I provide a ratchet holding device which permits the rotation of the shaft 10 for adjusting the compression of the spring to properly counterbalance the curtain. This device consists of a head or disk 38 secured on one end of the shaft and provided with a number of radial holes 39 at its periphery, in which the end of a bar can be placed to turn the shaft 10, and also adapted to receive a locking pin 40. The locking pin is held in a bracket 41 secured to the end bracket 18 of the casing. To hold the spring 37 central and free of the shaft I provide the nut with a central projection 42 and the fixed abutment 35 with a similar central projection 43 which projections enter within the ends of the spring. It will now be clear that the counterbalance of my invention is a compact strong device, that I do not have to bend nor distort nor even fasten the ends of the spring, that the spring is in its best possible condition for constant use, being merely compressed and extended and that it does not have to resist any other distorting strain. This form of spring is the cheapest form to manufacture and is the least liable to break in use. It will also be clear that I am enabled to minimize the working friction of my device and keep it constantly lubricated as the square tube and the drum form a casing which is tightly closed, in which to hold the lubricant. There is no end friction to absorb power except at the ends of the spring, as the expansive force of the spring is resisted by the head 35 and the nut, both of

which are carried on the shaft 10. To reduce friction I preferably fasten the head 35 free of the head 15.

As indicated hereinbefore either the drum or the shaft may be maintained stationary and the other element rotated and in Figures 4 to 8 inclusive I have shown a form of my device in which the drum is stationary and the shaft rotates.

As described, the device shown in Figures 1 to 3 is arranged to apply the increasing force of the spring to the curtain as it descends to properly counterbalance it at all times. There are other forms of movable closures in which the weight to be counterbalanced is substantially constant. This would be exactly true of a door or closure which was arranged to slide vertically to open and close, and I provide means for compensating the variable force of the compression spring to provide a counterbalancing force which is substantially constant, or I could go even further than this and produce such variations in counterbalancing force as to properly counterbalance a closure which requires a variable lifting force to counterbalance it which force does not change in consonance with the changing force of the spring.

In said Figures 4 to 8 I have illustrated a horizontal folding door of the kind used to close the doors of warehouses, etc. Doors of this character usually consist of an upper section 50 and a lower section 51, the two sections hinged together at their horizontal meeting edges by the hinges 52. The upper section is hinged to the wall of the building by hinges 53 above the door opening 54. The lower edge 55 of the lower section is guided vertically so that when the door is lifted it will fold on the intermediate hinges to the position shown in dotted lines in Figure 5. Vertical guide grooves 56 are provided one at each edge of the door opening, and the lower part of the door is provided with guide shoes 57 adapted to slide in the grooves. The shoes are pivoted to the edges of the door by horizontal pivot pins 58 mounted in brackets 59. For lifting a door of this character I provide a horizontal shaft 60 rotatably mounted in brackets 61 secured to the wall of the building above the door. On one end of the shaft I secure a gear 62 and I provide a pinion 63 meshing with the gear and a chain wheel 64 and chain 65 for rotating the shaft 60 by hand. For counterbalancing the weight of the door, which is substantially constant, I provide a tubular housing 64 surrounding the middle portion of the shaft 60; in the form shown this tubular housing is formed of a square tube. I close the ends of the tube by heads 65 and 66 providing central holes in the heads through which the shaft 60 projects and by which the tube is

1
rotatably mounted on the shaft. As in the former instance the shaft shown in the drawings is square within the tube and I twist it to form the long pitch screw thread 67. It 5 should be understood that the twisted square shaft is typical merely of a shaft provided with one or more spiral grooves forming suitable threads for co-operation with the nut 26. In this form of my de- 10 vice instead of the shaft being held stationary I allow it to rotate and I hold the other member stationary. For this purpose I provide a third bracket 68 which has a bearing 69 in which I rotatably mount one 15 end of the square tube 64 by means of the head 65 which I project beyond the end of the tube, providing it with a cylindrical part to fit within the bearing. On the outer end of the head 65 I secure a ratchet de- 20 vice 70 similar to the one already described and held locked against rotation by a pin 71 which projects through a hole provided in an arm 72 on the bracket 68. I pro- 25 vide a suitable shaft and tube interengaging member such as one of the square nuts 26 fitting within the square tube 64 and fitting the threaded part of the shaft and I pro- 30 vide one of the compression springs 37 ar- ranged between the nut and one of the abutments 35 fixed on the shaft as in the former instance, so that as the shaft is rotated to lift the door the spring is per- 35 mitted to extend and is compressed as the door is lowered. This compression of the spring increases its counterbalancing force but the force necessary to counterbalance the door is substantially constant, though it may, of course, vary slightly. To compensate for the varying power of the spring I provide 40 coned pulleys 73 on the shaft 60 connected by cables 74 to the lower edge of the door; the upper ends of the cables are fastened to the large ends of the pulleys and the cables are adapted to wind toward the small 45 ends of the pulleys as the door is lifted, and I so arrange the screw and other parts that as the door descends and thus unwinds the cables to the large ends of the pulleys, the spring is compressed, and it can readily 50 be understood that the variation of the strength of the spring can be arranged to be exactly compensated for, by the varying diameter of the coned pulleys, also that if the force for lifting the door varies from one 55 extreme to the other, that this variation can readily be allowed for in the taper of the pulleys and the strength of the spring, so that practically, the door will be exactly counterbalanced in all positions. 60 It should be understood that while I have illustrated a square nut for engagement with the shaft, and a square tube in which the nut slides, these parts may be varied within the scope of the appended claims without 65 departing from the spirit of my invention.

I therefore contemplate forming the engagement between the shaft, nut and tube, in many ways.

The preferred form is shown in Figures 9 and 10. The round shaft 80 has one or 70 more spiral grooves 81 milled therein. These grooves may be round or square bottomed or of any desired form. An annular collar 82 is provided with one or more internal spiral ribs 83 for engaging the grooves 81. The 75 number of spiral grooves 81 in the shaft 80 may be varied and may comprise one or more. The annular collar 82 is preferably formed of phosphor bronze, or a like metal, to reduce friction between the engaging 80 parts. This collar is secured as by a driven fit or by suitable set bolts 84 in a dog 85 which may be formed of cast iron, although it is to be understood that the dog 85 and collar 82 may be formed of a single piece of 85 phosphor bronze or the like if desired, as shown in Figure 10.

To prevent rotation of the dog 85 and collar 82 carried thereby relative to the tubular casing 11 which forms the drum of the curtain or shutter, I employ one or more angle irons 86, which are securely bolted to the inner periphery of the tubular casing 11. The inwardly extending flanges 87 of the angle irons 86 extend longitudinally through 95 the drum 11 and engage in suitable grooves 88, which grooves 88 are formed in the longitudinal ribs 89, which extend outwardly from the periphery of the dog 85. The grooves 88 are of sufficient width that the 100 flanges 87 will be loosely embraced, whereby the dog 85 and collar 82 can freely slide within the casing 11 and at the same time rotation of the dog 85 will be effectively prevented. This drum is preferably packed 105 with grease, and as the drum is closed by suitable heads, lubrication is assured.

As hereinbefore pointed out, the dog 85 and the collar 82 may be formed of a single piece of phosphor bronze or a like metal, 110 wherein the resistance to wear is very great if so desired; such a construction is shown at 90 in Figure 10. It will also be apparent that the longitudinal ribs 89' which extend outwardly from the periphery of the mem- 115 ber 90, may engage in suitable channel mem- bers 91 secured to the inner periphery of the tubular casing 11 and extending longitudinally therethrough. In either form there are suitable interengaging parts which per- 120 mit longitudinal movement without permitting rotation.

The drum 11 is provided with suitable heads 15' and 16' shown in Figure 12, and it forms the supporting cylinder for the 125 flexible shutter 12.

As I am aware that many modifications of my invention will readily suggest themselves to one skilled in the art, I do not intend to limit or confine my invention to the specific 130

embodiments herein shown and described, although in the various forms shown the prominent and important aspect of my invention is the utilization of the expansive force of a coiled compression spring as a counterbalancing force.

I claim:

1. In combination, a vertically movable member varying in weight throughout its various vertical positions, a spring having a varying expansive stress opposing the varying weight of said vertically movable member throughout its vertical movement, the varying expansive stress of said spring counterbalancing said vertically movable member throughout its vertical movement.
2. In combination a vertically movable member, a counterbalance comprising a drum and a screw shaft having relative rotatable movement, an abutment having rectilinear movement along said screw shaft, a relatively stationary abutment, a spring interposed between said relatively movable and stationary abutments, said spring being compressed upon descent of said vertically movable member whereby an increasing rectilinear force is set up to properly counterbalance the increasing weight of said member.
3. In combination a vertically movable member, a counterbalance comprising a drum and a screw shaft having relative rotatable movement, an abutment having rectilinear movement along said screw shaft, a relatively stationary abutment, a spring interposed between said relatively stationary and movable abutments, said spring expanding upon ascent of said vertically movable member whereby a decreasing rectilinear force is set up to properly counterbalance the decreasing weight of said member throughout its various vertical positions.
4. In combination a vertically movable member, a counterbalance comprising a drum and a screw shaft having relative rotatable movement, an abutment having rectilinear movement along said screw shaft, a relatively stationary abutment, a spring interposed between said relatively stationary and movable abutments, the compression of said spring upon descent of said vertically movable member and expansion of the spring upon ascent of said vertically movable member setting up a counterbalancing force varying with the varying weight of said member to properly counterbalance the same throughout its various vertical positions.
5. In combination a vertically movable member, a counterbalance comprising a drum and a screw shaft having relative rotatable movement, an abutment having rectilinear movement along said screw shaft, a relatively stationary abutment, a spring interposed between said relatively stationary and movable abutments, said spring being com-

pressed upon descent of the said vertically movable member whereby a force is set up in opposition to the relative rotative movement between said drum and said shaft, the force set up by said spring increasing with the increasing weight of said member to properly counterbalance the same throughout its various positions.

6. In combination a vertically movable member, a counterbalance comprising a sleeve member and a shaft having relative rotatable movement, an abutment having rectilinear movement along said shaft, a second abutment fixed relative said first abutment, a spring member freely interposed between said abutments and adapted to be compressed therebetween upon descent of the vertically movable member, setting up a rectilinear force in said spring to counterbalance said member throughout its various vertical positions.

7. In combination, a rotatable drum, a relatively fixed abutment therein, a second abutment interlocked for rotation with said rotatable drum, said second abutment having rectilinear movement within said drum, a spring interposed between said relatively fixed and movable abutments, and means for converting rotation of said rotatable drum into rectilinear movement of said second abutment whereupon said spring is contracted or expanded without twisting or winding the same.

8. In combination, a rotatable drum, a relatively fixed abutment therein, a second abutment interlocked for rotation with said rotatable drum, said abutment having rectilinear movement within said drum, means for converting rotation of said drum into rectilinear movement of said second abutment and a coiled spring interposed between and having its opposite ends freely engaging said relatively fixed and relatively movable abutments respectively.

9. In a counterbalance, a sleeve member and a shaft having relative rotation, an abutment interlocked for rotation with the rotatable member, said abutment having rectilinear movement along said shaft, a spring interposed between and having its opposite ends freely engaging said movable and stationary abutments respectively, said spring member being compressed by relative movement between said abutments upon application of a varying force to be counterbalanced, whereupon a varying counterbalancing force is set up in said spring in opposition to said first force.

10. In combination, a winding drum for shutter doors, a relatively stationary abutment, a spring disposed within said winding drum, one end of said spring freely engaging said relatively stationary abutment, an abutment arranged for rotation with said drum, said abutment compressing said spring with-

out twisting or otherwise subjecting the same to torsional strain.

11. In combination, a winding drum, a relatively stationary shaft carrying said drum, head members closing off the ends of said drum, a relatively fixed abutment on said shaft, a sleeve member rotatably mounted at one end upon said abutment and connected at its opposite end with one of said head members, and means in said sleeve for counter-balancing the drum upon rotation thereof.

12. In combination, a winding drum, a

relatively stationary shaft carrying said drum, head members closing off the ends of 15 said drum, a relatively fixed abutment on said shaft, an abutment interlocked for rotation with said drum, said abutment having axial movement along said shaft and a spring member interposed between said relatively stationary and axially movable abutment, said drum forming a lubricant chamber.

In witness whereof I hereunto subscribe my name this 1st day of February, 1919.

SAMUEL P. SMURR.
